TRANSMISSION CONTROL CIRCUITS IN
TWO-WAY SIGNALING SYSTEMSBjorn G. Bjornson, Brooklyn, N. Y., assignor to
Bell Telephone Laboratories, Incorporated, New
York, N. Y., a corporation of New York

Application February 3, 1932, Serial No. 590,537

11 Claims. (Cl. 178—44)

This invention relates to two-way signaling systems and particularly to the signal-controlled means employed therewith for suppressing echoes and preventing singing.

5 An object of the invention is to improve the operation characteristics of long, two-way signaling systems employing signal-controlled apparatus for suppressing echoes and preventing singing.

10 To obtain proper operation of a long two-way signaling system, including over at least a portion of its length a four-wire circuit having one path adapted for transmission in one direction, and another path adapted for transmission in the opposite direction, it has been found necessary in the past to employ signal-controlled apparatus for effectively disabling one of the associated one-way paths while signal transmission is taking place over the other, so as to prevent echo currents or reflected currents from being transmitted back to the transmitting end of the system and causing a disturbance or singing. The disabling apparatus usually comprises means, such as an amplifier-rectifier control circuit for diverting a portion of the signaling current from one path and utilizing it to control the open-circuiting or short-circuiting of the oppositely directed path or to control in proper manner the operation characteristics of an amplifier in the oppositely directed path.

15 In certain circuits of the prior art, these signal-controlled devices or echo suppressors as they are commonly called, one of which is associated with each two-wire path, are located at some intermediate station, for example, at a midway point. In other circuits of the prior art, the two units of the echo suppressor are located at or near the ends of the four-wire circuit. The latter arrangement, the so-called terminal echo suppressor, may be either 20 of the "sender" or the "receiver" type. In the "sender" type of terminal echo suppressor, the suppressor units located near each terminal comprise a suppressor responsive to signals in the outgoing two-wire circuit to disable the incoming two-wire circuit, and means responsive to signals in the incoming circuit to disable the suppressor.

25 In the "receiver" type of terminal echo suppressor, the suppressor units located near each terminal of the four-wire circuit, comprise a suppressor responsive to signals in the incoming two-wire circuit to disable the outgoing two-wire circuit, and means responsive to signals in the outgoing two-wire circuit to disable the suppressor.

30 The invention relates to improvements in two-

way signaling systems, for example, two-way telephone systems, employing echo suppressors of the above mentioned types, the improvements residing in the provision of means for facilitating break-ins by a listening party after one party has obtained exclusive control of the system. This is accomplished by the provision of means under control of the first talker's signaling currents operative a given time after he has obtained control of the system, for rearranging the control circuits of the system so as to bias the system from the standpoint of break-ins in favor of the listener. While the system is so biased, the listener can, on perceiving a pause by the first talker, immediately break in, gain control of the system for his own signaling currents and shut out the first talker.

35 The nature of the circuits of the invention and their advantages will be clear from the following detailed description thereof when read in connection with the accompanying drawings:

40 Fig. 1 of which shows schematically a four-wire toll telephone circuit employing terminal echo suppressors of the "receiver" type and embodying the invention;

45 Fig. 2 of which shows schematically a four-wire toll telephone circuit employing terminal echo suppressors of the "sender" type, and embodying the invention;

50 Fig. 3 of which shows schematically a four-wire toll telephone circuit employing echo suppressors of the mid-point type and embodying the invention; and

55 Fig. 4 of which shows schematically a four-wire toll telephone circuit employing the combination of receiver terminal with mid-point echo suppressors and embodying the invention.

For convenience the invention will be described as applied to systems for the two-way transmission of speech waves, but it is to be understood that the principles of the invention apply equally well to systems for the two-way transmission of signal waves in general of frequencies within or outside the speech frequency range, such as waves representing speech, entertainment programs comprising music as well as speech, etc.

60 The four-wire toll telephone circuit of Fig. 1 comprises a one-way transmission path EA including the one-way amplifying devices 1 and 2 for repeating telephonic currents in the direction from west to east between the west two-way telephone circuit L_1 and the east two-way telephone circuit L_2 , and the one-way transmission path WA including the one-way amplifying devices 3 and 4 for repeating telephonic currents

in the direction from east to west between the east two-way telephone circuit L_2 and the west two-way telephone circuit L_1 . In well known manner, the oppositely directed one-way transmission paths EA and WA may be connected in substantially conjugate relation with each other and in energy transmitting relation with the telephone circuits L_1 and L_2 , respectively, by the hybrid coil transformers H_1 and H_2 , and the associated balancing networks N_1 and N_2 .

A "receiver" type terminal echo suppressor is located near the west end of the four-wire circuit, which will be referred to hereinafter as station A, and another "receiver" type terminal echo suppressor is located near the east terminal of the four-wire circuit, which will be referred to hereinafter as the station B.

The terminal echo suppressor located at station A includes a control circuit 5 having its input bridged across the output of the path WA, and comprising a relay-controlling device 6, which may be a vacuum tube amplifier-rectifier device such as is well known in the art, and the windings of mechanical relays 7, 8 and 9 connected in parallel to the output of the control device 6. The mechanical relay 9 is made to operate in response to operation of the control device 6 a definite interval of time, d_1 seconds, after the relays 7 and 8 have operated, for example, by the insertion of a delay circuit 10 of any suitable type between the output of the device 6 and the winding of mechanical relay 9 designed to delay the transmission of energizing current to the winding of relay 9 for a time interval of d_1 .

The terminal echo suppressor at station A also includes a control circuit 11 having its input connected across the path EA in the output of the amplifying device therein, and comprising a relay-controlling device 12, similar to the device 6, and the windings of mechanical relays 13 and 14 connected in parallel to the output of the device 12. The mechanical relay 14 is made to operate in response to operation of the control device 12 a definite time interval T after the device 12 has operated, for example, by the insertion of electrical delay circuit 15, similar to the delay circuit 10, between the output of the device 12 and the winding of mechanical relay 14, designed to delay the transmission of energizing current to the winding of relay 14 for the interval of time T, where T is the transmission time between station A and station B over the transmission path EA.

In the input of the path EA at station A between the input of the amplifying device 1 and the hybrid coil H_1 are the normally closed switch contacts 16 which are adapted to be opened by operation of the mechanical relay 7 when its winding is energized by operation of the control device 6 in control circuit 5. In the control circuit 11 between the output of the delay circuit 15 therein and the winding of mechanical relay 14, are the normally closed switch contacts 17 adapted to be opened by the relay 8 when its winding is energized by operation of control device 6. In the output of the control device 12 in control circuit 11 between the point of connection of delay circuit 15 thereto and the winding of mechanical relay 13 are the normally open switch contacts 18 adapted to be closed by the mechanical relay 9 when its winding is energized by operation of the control device 6.

In the path WA at a point therein at station A between the point of connection thereto of the

control circuit 5 and the output of the amplifying device 4 are the normally closed switch contacts 19 adapted to be opened by relay 13 when its winding is energized in response to operation of the control device 12 in control circuit 11. In the output of the control circuit 5 between the output of the control device 6 therein and the windings of mechanical relays 7, 8 and 9, are the normally closed switch contacts 20 adapted to be opened by relay 14 when its winding is energized in response to operation of control device 12 in control circuit 11.

The terminal echo suppressor at station B includes the control circuit 21 having its input bridged across the output of the path EA, and comprising a relay-controlling device 22, similar to the devices 6 and 12 at station A, and the windings of mechanical relays 23, 24 and 25 connected in parallel to the output of the device 22. Relay 25 is made to operate after the relays 23 and 24 in response to operation of the device 22 by a time interval of d_1 , for example, by the insertion of a delay circuit 26 between the output of the control device 22 and the winding of relay 25 to delay the transmission of energizing current to the winding of relay 25 for the interval d_1 .

The terminal echo suppressor at station B also includes a control circuit 27 having its input connected across the input of the path WA in the output of the amplifying device 3 therein, and comprising a relay controlling device 28, similar to the device 22, and the windings of mechanical relays 29 and 30 connected in parallel to the output of the device 28. The mechanical relay 30 is made to operate after operation of the control device 28 by a time interval of preferably T, for example, by the insertion of the delay circuit 31 in the control circuit 27 between the winding of relay 30 and the output of the control device 28, to delay the transmission of energizing current to relay 30 from the output of the control device 28 for the time interval T.

In the input of the path WA at station B are the normally closed switch contacts 32 adapted to be opened by relay 23 when its winding is energized in response to operation of control device 22 in control circuit 21. In the control circuit 27 between the output of the delay circuit 31 and the winding of relay 30 are the normally closed switch contacts 33 adapted to be opened by relay 24 when its winding is energized by operation of the control device 22. In the output of the control circuit 27 between the point of connection thereto of delay circuit 31 and the winding of mechanical relay 29 are the normally open switch contacts 34 adapted to be closed by relay 25 when its winding is energized in response to operation of the control device 22 in the control circuit 21. In the output of the control circuit 21 between the output of the control device 22 therein and the windings of the mechanical relays 23, 24 and 25 are the normally closed switch contacts 35 adapted to be opened by relay 30 when its winding is energized in response to operation of the control device 28 in control circuit 21.

The operation of the system of Fig. 1 will now be described. It will be assumed that the circuit is inactive so that the switching contacts controlled by the echo suppressor circuits at both stations A and B are in their normal condition as indicated in Fig. 1. Then, let it be assumed that a west subscriber associated with the two-way circuit L_1 starts to talk and that thereafter, but within a time interval of T, an east subscriber associated with the circuit L_2 also starts to talk.

The west subscriber's speech current received over the circuit L_1 at station A will be impressed by hybrid coil H_1 upon the input of the west to east transmission path EA over which it will be transmitted after amplification by the amplifying device 1 at station A to the distant station B where it will be amplified again by the amplifying device 2. The main portion of the west subscriber's speech current in the output of the amplifying device 2 will be transmitted over the output of the path EA to the hybrid coil H_2 which will impress it upon the circuit L_2 over which it will be transmitted to the listening east subscriber. 5

Meanwhile, a small portion of the west subscriber's speech current at station A is diverted in the control circuit 11 and causes the operation of the control device 12 therein. The operation of control device 12, however, will not cause energizing currents to be supplied to the winding of the mechanical relay 13 because of the normally open switch contacts 18 in the input of that relay. The operation of control device 12 will cause energizing currents to be supplied to the winding of mechanical relay 14, but only after a delay of T 10 due to the action of the delay circuit 15. This means that the relay 14 will operate substantially at the same time as the west subscriber's speech currents arrive at the station B over the path EA, to open the normally closed switch contacts 20 29 in the output of control circuit 5 to disable the inputs of mechanical relays 7, 8 and 9 connected to the output of the control device 6. 25

The portion of the west subscriber's speech currents diverted into control circuit 21 at station B will cause the operation of control device 22. The operation of control device 22 will cause energizing currents to be supplied directly to the windings of relays 23 and 24 and through delay circuit 26 to the winding of relay 25. Relay 23 30 will operate immediately to open switch contacts 32 in the input of the path WA rendering that path inoperative thereafter to transmit to the circuit L_1 at station A or to the input of control circuits 27 and 5. Relay 24 will operate simultaneously with relay 23, to open the switch contacts 33 in control circuit 27 thereby disabling the input of relay 39. The west subscriber has now obtained exclusive control of the switching circuits at both station A and station B. 35

If the east subscriber associated with circuit L_2 starts to talk immediately after the west subscriber does so, a portion of the former's speech currents may pass the point in path WA where switch contacts 32 are located before these contacts have been opened in response to the west subscriber's speech currents, and will cause operation of the control device 23 in control circuit 27 at station B and of control device 6 in the control circuit 5 at station A. A portion of the east subscriber's speech currents will also be transmitted over the output of the path WA to circuit L_1 and will be heard by the west subscriber associated therewith. The operation of control device 6 will not cause false operation of relays 7, 8 and 9 at station A because the input of these relays has been previously disabled by the opening of switch contacts 28 in response to the west subscriber's speech currents. 40

The operation of the control device 28 will not cause energizing currents to be supplied to the winding of mechanical relay 29 because the switch contacts 34 in its input are still open. The operation of control device 28, however, will cause energizing current to be supplied to the winding of mechanical relay 30 but with the delay 45

of T caused by the delay circuit 31 in the output of the device 28. The transmission of energizing current to the winding of relay 30 will be delayed for the time interval T by delay circuit 31 and will therefore not be effective in causing operation of that relay because its input will have been previously disabled by the opening of switch contacts 33 in response to the west subscriber's speech currents. Then, the west subscriber has obtained complete control of the switching circuits at both stations. 50

Substantially d_1 seconds after the west subscriber has obtained control of the switching circuits in the manner described, the energizing currents being transmitted through the delay circuit 26 in the output of control circuit 21 cause the winding of relay 25 to be energized. Relay 25 then operates to close and maintain closed the normally open switch contacts 34 in the output of control circuit 27, thereby biasing the four-wire circuit as regards break-ins in favor of the east subscriber. Now, if the east subscriber breaks in during a pause by the west subscriber sufficiently long to enable the relay 23 and the relay 24 to release momentarily, his (the east subscriber's) speech currents diverted into control circuit 27 at station A, will cause operation of the control circuit 28 therein to immediately energize the winding of relay 29 causing the normally closed switch contacts 36 in the output of the path EA to be opened to disable that path, and a time interval T later to energize the winding of relay 30 causing the normally closed switch contacts 35 in the output of control circuit 21 to be opened to disable that circuit as regards subsequent operation under control of the west subscriber's speech currents. A portion of the east subscriber's amplified speech currents transmitted over the path WA during this pause will be diverted into control circuit 5 at station A and will cause operation of the control device 6 therein to energize the windings of mechanical relays 7 and 8 in the output thereof. These relays will immediately operate respectively to disable path EA by opening switch contacts 16 therein and to 45 disable the input of relay 14 by opening switch contacts 11, thus giving complete control of the switching circuits to the east subscriber. 50

The operation of control device 6 after a delay of an additional interval of d_1 caused by delay circuit 16 will cause the winding of relay 9 to be energized and that relay will operate to close normally open switch contacts 18 in the output of control circuit 11, so as to bias the four-wire circuit as regards subsequent break-ins in favor of the west subscriber. 55

As indicated in Fig. 1, the relay 9 in control circuit 5 at station A and the corresponding relay 25 in control circuit 21 at station B should have a small hang-over, h_1 , in their operation, and the relay 13 in control circuit 11 at station A and the relay 29 in control circuit 27 at station B should have a small hang-over, h_2 , in their operation. These hang-over times should be such as to keep relays 13 and 29 operated to maintain the switch contacts 19 in the path WA and the switch contacts 36 in the path EA open, respectively, until the dissipation of the energy which might have passed by the controlling suppressor before it came into operation. These hang-overs may be obtained by proper mechanical design of the relays to make them slow-releasing, or by utilizing in connection therewith auxiliary hang-over circuits, for example, such as disclosed in the patent to J. Herman, 1,798,202, issued March 75

31, 1931. The echo suppressor relay 7 at station A and the echo suppressor relay 23 at station B should also have sufficient hang-over in their operation to hold them operated for a slight time after the supply of speech currents to the control devices 6 and 22, respectively, ceases to prevent premature closing of the switch contacts 16 and 32, respectively.

Fig. 2 shows a circuit arrangement for facilitating break-ins by a listening party after one party has obtained exclusive control in a four-wire toll telephone circuit employing "sender" terminal echo suppressors.

The echo suppressor circuits at station A in the system of Fig. 2 includes a control circuit 37 having its input connected across the path EA at station A, and comprising a relay controlling device 38, which may be a vacuum tube amplifier-rectifier circuit, the winding of a mechanical relay 40 connected to the output of the control device 38 over a circuit 41, and the windings of mechanical relays 42 and 43 connected to be operated in parallel from the output of the control device 38 over a circuit 44 including the delay circuits 45 and 46. Connected around the portion of control circuit 44 including the delay circuit 46 of relay 43 is a by-pass circuit 47. The normally closed switch contacts 48 in the path WA at station A are adapted to be opened to open-circuit the output of the path WA by means of relay 49 in response to energization of its winding by the operation of control device 38. The normally closed switch contacts 49 in the path WA at station A are also adapted to be opened to open-circuit the output of path WA by relay 42 when its winding is energized by operation of the control device 38. The normally closed switch contacts 50 in by-pass circuit 47 are adapted to be opened to disable that circuit by relay 43 when its winding is energized by operation of the control device 38.

Bridged across the output of the path WA between the point of connection therein of switch contacts 48 and 49 and the hybrid coil H₁ is the input of a control circuit 51 comprising the control device 52, similar to the device 38, and the windings of mechanical relays 53, 54, 55 and 56 connected in parallel with the output of the control device 52. The operation of relay 56 is delayed with respect to that of relays 53, 54 and 55 in response to the operation of control device 52 for a small time interval d_1 by a delay circuit 57 of suitable design connected between the winding of relay 56 and the output of the control device 52.

The normally closed contacts 58 in the input of the control circuit 37 are adapted to be opened to disable that control circuit by relay 53 when its winding is energized in response to operation of the control device 52. The normally closed switch contacts 59 in the output of the control circuit 44 are adapted to be opened to disable the input of relay 42, by relay 55 when its winding is energized in response to operation of the control device 52. The normally closed switch contacts 60 in circuit 44 between delay circuit 45 and delay circuit 46 are adapted to be opened to disable the circuit 44, and therefore relays 42 and 43, by relay 54 when its winding is energized in response to operation of the control device 52. The normally open switch contacts 61 in the circuit 41 connecting the output of the control device 38 to the winding of relay 40, are adapted to be closed to render operative the

circuit 41, by relay 56 when its winding is energized by operation of the control device 52.

The echo suppressor circuits at station B in the system of Fig. 2 include a control circuit 62 having its input connected across the input of the path WA at station B, and comprising the relay controlling device 63, similar to the devices 52 and 38 at station A, the winding of a mechanical relay 64 connected to the output of the device 63 by a circuit 65, and the windings of mechanical relays 66 and 67 connected to be operated in parallel from the output of the control device 63 over a circuit 68 comprising the delay circuits 69 and 70.

Connected around the portion of the circuit 68 including the delay circuit 70 and relay 67 is the by-pass circuit 71.

The normally closed switch contacts 72 in the output of the path EA are adapted to be opened to open-circuit that path by relay 64 when its winding is energized in response to operation of the control device 63. The normally closed switch contacts 73 in the output of the path EA are adapted to be opened also to open-circuit that path by relay 66 when its winding is energized in response to operation of the control device 63. The normally closed switch contacts 74 in the by-pass circuit 71 are adapted to be opened to disable that circuit by relay 67 when its winding is energized in response to operation of the control device 63.

Connected across the output of the path EA between the switch contacts 72 and 73 therein and the hybrid coil H₂ is the input of a control circuit 75 comprising the relay-controlling device 76, similar to the device 63, and the windings of mechanical relays 77, 78, 79 and 80 connected in parallel across the output of the control device 76. The relay 80 is made to operate a small time interval, d_1 , after relays 77, 78 and 79 have operated in response to operation of the control device 76 by means of a delay circuit 81 of suitable design connected between the winding in response to operation of the control device 76.

The normal closed switch contacts 82 in the input of the control circuit 62 are adapted to be opened to disable that circuit by operation of relay 77 when its winding is energized in response to operation of the control device 76. The normally closed switch contacts 83 in the output of the circuit 68 are adapted to be opened to disable relay 66, by relay 79 when its winding is energized in response to operation of control device 76. The normally closed switch contacts 84 in the circuit 68 between delay circuits 69 and 70 are adapted to be opened to disable that circuit, by relay 78 when its winding is energized in response to operation of control device 76. The normally open switch contacts 85 in the circuit 65 are adapted to be closed to render operative the circuit 65 connecting the winding of relay 64 to the output of the control device 63, by relay 80 when its winding is energized in response to operation of the control device 76.

The delay circuits 45 and 46 in the circuit 44 at station A, and the delay circuits 69 and 70 in the circuit 68 at station B are each designed to produce a delay T in the transmission of currents therethrough, where T is the transmission time between the stations A and B over one of the one-way transmission paths EA or WA.

The operation of the system of Fig. 2 will now be described. It will be assumed that the west

subscriber associated with circuit L_1 terminating at station A starts to talk before the east subscriber associated with circuit L_2 terminating at station B starts to talk. The west subscriber's speech currents will be impressed by the hybrid coil H_1 upon the input of the path EA and transmitted thereover towards station B. A portion of the west subscriber's speech currents will be diverted into the input of the control circuit 31 5 causing the operation of the control device 38 therein.

The main portion of the west subscriber's speech currents will be transmitted out over the path EA to the distant station B being amplified in transit by the amplifying devices in that path. At station B, the main portion of the west subscriber's amplified speech currents will be transmitted over the path EA to the hybrid coil H_2 which will impress it upon the circuit 20 L_2 over which it will be transmitted to the listening east subscriber.

A small portion of the west subscriber's speech currents at station B will be diverted into the control circuit 75 causing the operation of the control device 76 therein. The operation of the control device 76 will cause energizing current to be supplied to the windings of mechanical relays 77 to 83. Relay 77 will operate immediately to open the normally closed switch contacts 82 in the input of the control circuit 62 making that circuit thereafter inoperative to transmit speech currents from the east subscriber thereafter received from the path WA. Relay 78 will operate simultaneously with relay 77 to open the normally closed switch contacts 84 in the output of the delay circuit 69 in circuit 68 thereby preventing any currents which may be stored in the delay circuit 69 before the switch contacts 82 in the input of control circuit 62 have opened from being transmitted to the delay circuit 79 or to the circuit 71. The relay 79 will operate simultaneously with relays 77 and 78 to open the normally closed switch contacts 23 in the input of the relay 66 thereby preventing false operation thereafter of that relay by speech currents which may have been stored in the delay circuit 70 at the time relay 77 operates to disable the input of the control circuit 62. Meanwhile at station A the operation of the control device 38 under control of the west subscriber's speech currents has caused energizing currents to be transmitted through delay circuit 45 in circuit 44 which will be divided between the by-pass circuit 47 and the input of the delay circuit 46 in circuit 44. The portion transmitted through the by-pass circuit 47 will cause the winding of relay 42 to be energized, and the relay 42 will then operate immediately to disable the path WA at station A by opening the normally closed switch contacts 49 in that path. Because of the delay of T introduced by delay circuit 45, the relay 42 will operate to disable the path WA by opening switch contacts 49 therein substantially at the same time as the relays 77 to 79 have operated at station B to disable the control circuits thereat which normally would be responsive to the east subscriber's speech currents. The west subscriber's speech currents now have obtained complete control of the switching circuits at both terminal stations.

If the east subscriber associated with the circuit L_2 starts to talk immediately after the west subscriber associated with the circuit L_1 , it will be apparent that with the circuit in the oper-

ated condition described, the east subscriber will not be able to get his speech currents through to the west subscriber or to seize control of the switching circuits away from the west subscriber because the switch contacts in their path will have been previously opened in response to the west subscriber's speech currents before the east subscriber's currents have reached the switching points.

Now, the portion of the energizing currents transmitted to the input of delay circuit 46 in the circuit 44 will be delayed in transmission there-through for another interval of T after which it will be supplied to relays 42 and 43. Relay 43 will then operate to open the normally closed switch contacts 88 in the by-pass circuit 47 thus cutting off the supply of current to the relay 42 over that circuit. However, relay 42 will not release because it will be maintained energized by the currents from the output of delay circuit 46 transmitted through unilateral device 157 to the winding of that relay.

Substantially d_1 seconds after relays 77 to 79 have operated at station B, relay 80, the energization of the winding of which has been delayed for that interval of time due to the action of delay circuit 81, will operate to close the normally open switch contacts 85 in the circuit 65 at station B rendering that circuit operative thereafter to supply energizing current to the winding of relay 64 immediately on operation of the control device 63 in the path 62. Then, the east subscriber on perceiving a pause in the continuous transmission of the west subscriber's speech currents sufficiently long to cause relays 77 and 42 at stations B and A, respectively, to release, may break in and seize exclusive control of the switching circuits at both terminal stations during the pause in the following manner.

The east subscriber's speech currents will be impressed upon the input of the path WA by hybrid coil H_2 . The main portion will be transmitted thereover to the distant station A, and a small portion will be diverted into control circuit 62, the switch contacts 82 therein being in the closed condition during the pause and will cause the operation of the control device 63. The operation of the control device 63 will cause energizing currents to be transmitted both to the circuit 68 and, the switch contacts 85 still being in the closed condition due to the hangover of h_1 in the operation of relay 80 controlled by the west subscriber's speech currents, also to the circuit 65. The energizing current impressed upon the circuit 65 will be immediately transmitted there-over to energize the winding of control relay 64 which will immediately operate to open the normally closed switch contacts 72 in the output of the path EA making that path thereafter inoperative to transmit the west subscriber's speech currents to the circuit L_2 . The energizing currents transmitted to the circuit 68 from the output of control device 63 will be delayed in that circuit in transmission through delay circuit 69 for an interval of T after which they will be divided between the by-pass circuit 71 and the delay circuit 70. The portion of the currents transmitted over the by-pass circuit 71 will cause energizing currents to be transmitted to the winding of relay 66 causing that relay to operate immediately to put an additional open circuit in the output of the path WA by opening normally closed switch contacts 73. The currents transmitted to delay circuit 70 will be delayed therein for a time in-

5 interval of T and subsequently will cause operation of relay 67 to disable the by-pass circuit 71 and through uni-lateral device 158 will maintain the relay 66 operated for the additional time interval T in a manner similar to that explained above for the corresponding apparatus at station A.

Meanwhile, the east subscriber's speech currents which have been transmitted over the path 10 WA will arrive at station A. The main portion of these currents will be transmitted from the output of the path WA to the hybrid coil H_1 which will impress it on circuit L_1 over which it will be transmitted to the listening west subscriber. A 15 portion of the east subscriber's speech currents in the path WA at station A will be diverted into the control circuit 51 and cause the operation of the control device 52 therein to supply energizing currents to the windings of relays 53 to 56 connected to its output. Relays 53, 54 and 55 will operate simultaneously to open switch contacts 58 in the input of control circuit 37, switch contacts 59 in the input of control relay 42 and switch contacts 60 in circuit 44 to seize control of the 20 switching circuits at the station A for the east subscriber. Because of the delay of T introduced by delay circuit 69 in the circuit 68 at station B, it will be seen that the control relay 66 at that 25 station operates to seize control of the switching circuits thereat for the east subscriber substantially at the same time as the relays 53, 54 and 55 at station A operate to seize control of the switching circuits thereat for the east subscriber. 30

A period of time d_1 after relays 53 to 55 at station A have operated, the energizing currents from the output of control device 52, which have been delayed in delay circuit 57, will cause the winding of relay 56 to be energized so as to cause 35 operation of that relay to close normally open switch contacts 61 in the circuit 56 biasing the system as regards subsequent operation of the switching control in favor of the west subscriber.

Proper operation of the system of Fig. 2 requires that the relays 54 and 55 controlled by the 40 control device 52 at station A, and the corresponding relays 78 and 79 controlled by the control device 76 at station B have a hang-over in their operation of substantially T , where T is the transmission time between station A and station B over one one-way path therebetween. As indicated in the drawings, the relay 55 controlled by the control device 52 at station A and the corresponding relay 89 controlled by the control device 76 at station B should be designed to have a 45 smaller hang-over in operation of h_1 , and the relay 49 controlled by the control device 38 at station A and the corresponding relay 64 controlled by the control device 63 at station B should have a smaller hang-over of h_2 in their operation. The hang-over times h_1 and h_2 should be 50 sufficiently long to keep relay 40 and relay 64 operated until the dissipation of the energy which may have passed by the input of the controlling suppressor before it came into operation. The suppressor relay 42 at station A and the suppressor relay 66 at station B also should be designed to have sufficient hang-over times in their operation to prevent premature closing of the switch contacts 49 in path WA and switch contacts 73 55 in the path EA with cessation of supply of speech currents to the control device 38 and the control device 63, respectively. The hang-overs in the several relays may be obtained by suitable mechanical design of these relays to make them slow-releasing to the required degree or by employing 60

in connection therewith suitable auxiliary hang-over circuits. The relay 53 controlled by the control device 52 at station A and the relay 77 controlled by the control device 76 at station B are preferably designed to have little or no hang-over in their operation so that they will release substantially instantaneously with cessation in the supply of voice currents to the controlling devices. 5

Fig. 3 shows a circuit arrangement for facilitating break-ins by a listening party after another party has obtained exclusive control in a four-wire toll telephone circuit employing echo suppressors of the "mid-point" type. 10

As indicated in Fig. 3, the echo suppressor circuit located at some point intermediate the two terminals of the four-wire circuits, which will be referred to hereinafter as station M, includes a control circuit 86 having its input connected across the path EA at station M, and comprising 15 a relay-controlling device 87, which may be a vacuum tube amplifier-rectifier circuit well known in the art.

A mechanical relay 88 is connected to the output of the control device 87 by a circuit 89. A 20 mechanical relay 90 is connected to the output of the control device 87 by a circuit 91. A mechanical relay 92 is connected to the output of control device 87 by a circuit 93 including a delay circuit 94. Two mechanical relays 95 and 96 are 25 connected across the circuit 93 in the output of the delay circuit 94 by a circuit 97 including a delay circuit 98. 30

Connected across the path WA at station M is the input of a control circuit 99 comprising a 35 relay-controlling device 100 similar to the device 87. A mechanical relay 101 is connected to the output of the device 100 by the circuit 102. A mechanical relay 103 is connected to the output of the device 100 by the circuit 104. A mechanical relay 105 is connected to the output of the device 100 by the circuit 106 including the delay circuit 107. The two mechanical relays 108 and 109 are 40 connected in parallel across the circuit 106 in the output of the delay circuit 107 by a circuit 110 including the delay circuit 111. 45

The normally closed switch contacts 112 in the path WA at station M are adapted to be opened to disable that path by relay 88 when its winding is energized by operation of control device 87. The normally closed switch contacts 113 in the output of circuit 106 are adapted to be opened to disable the input of relay 105 by relay 99 when its winding is energized by operation of the control device 87. The normally closed switch contacts 114 in the path WA are adapted to be opened to disable that path by relay 92 when its winding is energized by operation of control device 87. The normally closed switch contacts 115 in circuit 89 are adapted to be opened to disable the input of relay 88 by relay 95 when its winding is energized by operation of the control device 87. The normally open switch contacts 116 in circuit 104 are adapted to be closed to render the input of relay 103 operative by relay 96 when its winding is energized by operation of control device 87. 55

The normally closed switch contacts 117 in the path EA at station M are adapted to be opened to disable that path by relay 101 when its 60 winding is energized by operation of control device 100. The normally closed switch contacts 118 in the output of circuit 93 are adapted to be opened to disable the input of relay 92 by relay 103 when its winding is energized by operation 65 70 75

of the control device 100. The normally closed switch contacts 119 in the path EA at station M are adapted to be opened to disable that path by relay 105 when its winding is energized by operation of control device 100. The normally open contacts 120 in circuit 91 are adapted to be closed to render operative the input of relay 93 by relay 103 when its winding is energized by operation of the control device 100. The normally closed switch contacts 121 in circuit 102 are adapted to be opened to disable the input of relay 101 by relay 109 when its winding is energized by operation of the control device 100.

The operation of the system of Fig. 3 will now be described. It will be assumed that the west subscriber associated with the circuit L₁ starts to talk first.

The west subscriber's speech currents will be impressed upon the input of the path EA by hybrid coil H₁ at station A and after being amplified by the amplifier at that station will be transmitted over the path EA towards the distant station B. The main portion of the west subscriber's speech currents, after amplification by the various amplifiers in its path, will be transmitted out over the output of the path EA to the hybrid coil H₂ which will impress it on the circuit L₂ over which it will be transmitted to the listening east subscriber.

At the intermediate station M a small portion of the west subscriber's speech currents is diverted into the control circuit 96 and will cause the operation of the control device 87 therein. The operation of the control device 87 will supply energizing current to the relay 88 over the circuit 99 and will also supply energizing current to relay 92 over the circuit 93 through the delay circuit 94, and will supply energizing current to the windings of relays 95 and 96 over circuit 93 through delay circuit 94 and over circuit 97 through delay circuit 98.

Relay 88 will immediately operate whereas the operation of relay 92 will be delayed for a time interval of T where T is the transmission time between the station A and station B over the path EA, and relays 95 and 96 will operate after a delay of T+d₁, where d₁ is any desired time interval.

The operation of relay 88 will open the normally closed switch contacts 112 in the path WA at station M rendering that path inoperative thereafter to transmit the east subscriber's speech currents to the west subscriber associated with the circuit L₁ or to the control circuit 99 at station M.

After an additional time interval T provided by the delay circuit 94 in the circuit 93, relay 92 will operate to further disable the path WA at station M by opening the normally closed switch contacts 114 therein. An interval of time d₁ seconds later required for the energizing currents to be transmitted through delay circuit 98, the relays 95 and 96 will operate simultaneously. The operation of relay 95 will open normally closed switch contacts 115 in circuit 99 thereby disabling the input of relay 88, which will release after a hang-over interval of h₂ causing contacts 112 to return to their normal closed condition. Relay 98 will simultaneously operate to close normally open switch contacts 116 in the circuit 104, making that circuit operative thereafter to transmit energizing currents from the control device 100 to the winding of relay 103, when the control device 100 is operated in response to currents impressed upon the input of control circuit 99.

From the above description, it is apparent that if the east subscriber associated with the circuit L₂ terminating at station B starts to talk after the west subscriber but within the time interval of T, the former will get his speech currents started within the time T through to the west subscriber associated with the circuit L₁ over the path WA. In other words, the west subscriber can hear what the east subscriber says before the end of the time interval T. However the east subscriber's speech current transmitted over the path WA within the time interval T, although it will cause operation of the control device 100 in control circuit 99 at station M, will not be able immediately to seize control of the switching circuits at station M away from the west subscriber because of the open switch contacts in the input of relay 103, and the delay circuits 107 and 111 in circuits 106 and 110, respectively, providing a delay of T and of T+d₁ in the transmission of energizing current to relays 105, 108 and 109, respectively.

However, at the end of the interval T+d₁, relay 96 has operated to render circuit 104 operative and relay 95 has operated to disable the circuit 99 leading to the winding of relay 88, and the echo suppressor circuits are now biased in favor of the listening east subscriber associated with the circuit L₂ terminating at station B, and he (the east subscriber) on perceiving a pause in the west subscriber's speech transmission may break in and seize control of the switching circuits away from the west subscriber in the following manner.

The relays 95 and 96 have a small hang-over of h₁ seconds during which they will remain operated after the west subscriber stops talking. Now, if the east subscriber says something when he observes west pause, his (east's) speech currents will be impressed upon the path WA by hybrid coil H₂ at station B and will be transmitted over that path to station M arriving thereat at the time at which relay 92 has released during this same pause to return the switch contacts 114 in path WA to their normally closed condition. A portion of the east subscriber's speech currents, therefore, will be diverted into control circuit 99 causing the operation of control device 100 therein. The operation of the device 100, the circuit 104 being still in the operative condition in which the switch contacts 116 are closed because of the hang-over of h₁ in the operation of relay 96, will energize the winding of relay 103 causing that relay to open the normally closed switch contacts 118 in circuit 98 to prevent the west subscriber from regaining control of relay 92 at the end of the pause in his conversation.

At the end of the time interval T after control device 100 has been operated by the east subscriber's speech currents, the energizing currents which have been delayed in transmission through delay circuit 107, will be transmitted to the winding of relay 105 causing the operation of that relay to open normally closed switch contacts 119 in the path WA at station M, rendering that path inoperative thereafter to transmit the west subscriber's speech currents to the control circuit 99 or to the east subscriber associated with circuit L₂ over the output of the path EA. The east subscriber has now obtained exclusive control of the switching circuits of the system.

At the end of an additional interval of time of d₁ the energizing currents, which have been delayed in transmission through delay circuit 111, cause the operation of relays 108 and 109.

to render operative the circuit 91 by closing switch contacts 120 therein, and to render inoperative circuit 92 by opening normally closed switch contacts 121 therein. The system is now biased as regards break-ins in favor of the west subscriber and, on perceiving a pause by the east subscriber sufficient to cause relays 135 and 136 to release momentarily, he may now break in and seize control of the system away from the east subscriber in a manner similar to that described in connection with the converse condition.

The relays 108 and 109 controlled by the control device 100 have a small hang-over of h_1 , equivalent to that of relays 95 and 96 controlled by control device 87 and provided for a similar purpose. Relay 101 controlled by the control device 100 and relay 88 controlled by the control device 87 each have a small hang-over in their operation of h_2 . This hang-over is sufficient to insure that these relays will not release during the pause in the speech currents of the subscriber who has controlled their operation, to unblock the path over which the currents of the subscriber attempting to break in are being transmitted at the time these currents arrive at the blocking point in that path. These hang-over times may be obtained in well known manner by design of the several relays to make them slow-releasing to the required degree or by employing in connection with these relays auxiliary hang-over circuits.

Fig. 4 shows a circuit arrangement for facilitating break-ins by a listening party when one party has obtained control in a four-wire toll telephone circuit employing the "receiver" type of echo suppressors at the two terminal stations A and B and mid-point type suppressors at an intermediate station M.

The suppressor circuits at station A include a control circuit 121 having its input connected across the output of the path WA at station A, and comprising a relay-controlling device 122, such as a vacuum tube amplifier-rectifier circuit, and the windings of mechanical relays 123 and 124 connected in parallel to the output of the device 122. A delay circuit 125 for introducing a delay of d_1 seconds in the transmission of energizing currents to relay 124 when control device 122 is operated, is inserted between the output of the device 122 and the winding of relay 124, to insure that relay 124 operates a definite time after relay 123. The echo suppressor circuits also include the control circuit 126 having its input connected across the input of the path EA at station A, and comprising a relay-controlling device 127, similar to the device 122, and the winding of a mechanical relay 128 connected to the output of the device 127. The normally closed switch contacts 129 in the input of the path EA between the point of connection of control circuit 126 thereto and a hybrid coil H_1 , are adapted to be opened by relay 123 when its winding is energized by operation of the control device 122. The normally open switch contacts 130 in the output of control circuit 126 are adapted to be closed to render operative the input of relay 128, by relay 124 when its winding is energized in response to operation of the control device 122. The normally closed switch contacts 131 in the output of the path WA at station A east of the point of connection of control circuit 121 to the path WA, are adapted to be opened to disable the path WA, by

relay 128 when its winding is energized in response to operation of control device 127.

The echo suppressor circuits at station B include a control circuit 132 having its input connected across the output of the path EA at station B, and comprising a relay-controlling device 133 similar to the devices 122 and 127, and the windings of mechanical relays 134 and 135 connected in parallel to the output of the device 133. A delay circuit 136 connected between the output of the control device 133 and the winding of relay 135 is provided to produce a time delay of d_1 in the operation of relay 135 with respect to the operation of relay 134 in response to the operation of control device 133.

The echo suppressor circuits at station B also include a control circuit 137 having its input connected across the input of the path WA at station B, and comprising a relay-controlling device 138, similar to the device 133, and the winding of a mechanical relay 139 connected to the output of the device 138.

The normally closed switch contacts 140 in the path WA between the point of connection thereto of control circuit 137 and the hybrid coil H_2 , are adapted to be opened to disable the input of the path WA, by relay 138 when its winding is energized by operation of the control device 133. The normally open switch contacts 141 in the output of the control circuit 137 are adapted to be closed to render operative the input of relay 139, by relay 138 when its winding is energized by operation of control device 133. The normally closed switch contacts 142 in the path EA at station B to the west of the point of connection of the control circuit 132 to that path, are adapted to be opened to disable the output of the path EA, by relay 139 when its winding is energized in response to operation of the control device 138.

The echo suppressor circuits at station M include a control circuit 143 having its input connected across the path WA at station M, and comprising a relay-controlling device 144, similar to the device 133, and the windings of mechanical relays 145 and 146 connected in parallel to the output of the device 144. A delay circuit 147 providing a delay of T in the transmission of current therethrough, where T is the transmission time between station A and station B over the path EA or the path WA, is inserted between the winding of relay 146 and the output of control device 144, to delay the operation of relay 146 with respect to that of 145 by the time interval T in response to operation of control device 144.

The normally closed switch contacts 148 in the path EA at station M are adapted to be opened to disable that path, by relay 145 when its winding is energized in response to operation of control device 144. The normally closed switch contacts 149 in the control circuit 143 are adapted to be opened to disable the input of relay 145, by relay 146 when its winding is energized in response to operation of the control device 144.

The echo suppressor circuits at station M include a control circuit 150 having its input connected across the path EA at station M, and comprising a relay-controlling device 151, similar to the device 144, and the windings of mechanical relays 152 and 153 connected in parallel to the output of the device 151.

A delay circuit 144 is connected between the winding 153 and the output of the control device 151 to provide a delay of T in the operation of re-

lay 153 with respect to that of relay 152 in response to the operation of control device 151.

The normally closed switch contacts 155 in the path WA at station M are adapted to be opened

5 to disable the path WA, by relay 152 when its winding is energized by operation of control device 151. The normally closed switch contacts 156 in the output of control circuit 150 are adapted to be opened to disable the input of relay 152, 10 by relay 153 when its winding is energized by operation of control device 151.

The relays 145, 146, 152 and 153 in echo suppressor circuits at station M are designed to have a hang-over of T in their operation. The relay 15 124 in control circuit 121 at station A and the corresponding relay 135 in the control circuit 132 at station B are designed to have a smaller hang-over in their operation of h_1 , so as to maintain switch contacts 130 in control circuit 126 at station A and switch contacts 141 in control circuit 20 137 at station B, respectively, closed for a sufficient time interval after the control devices 122 and 133, respectively, release during a pause in the continuous transmission of the controlling 25 speech currents of the talking subscriber to enable the subscriber trying to break in to seize control of the switching circuits during that pause. The relay 128 in control circuit 126 at station A and the relay 139 in control circuit 137 at station 30 B are designed to have a hang-over in their operation of substantially T. These hang-over times may be provided by suitable mechanical design of the various relays to make them slow-releasing to the required degree, or by employing in connection with these relays suitable auxiliary hang-over circuits.

The operation of the system of Fig. 4 will now be described. It will be assumed that the west subscriber associated with the circuit L_1 terminating 40 at station A first starts to talk. His speech currents will be impressed by the hybrid coil H_1 upon the input of the path EA and transmitted thereover towards the distant station B.

The main portion of the west subscriber's 45 speech currents will be transmitted over the path EA being amplified en route by the various amplifying devices in that path, to the hybrid coil H_2 at station B which will impress it upon the circuit L_2 over which it will be transmitted to the 50 listening east subscriber. A small portion of the west subscriber's speech currents, however, will be diverted into the control circuit 126 at station A, causing the operation of the control device 127, 55 however, will not cause operation of the relay 128 in its output because of the normally closed switch contacts 130 in the input of that relay.

Another portion of the west subscriber's speech 60 currents will be diverted into the control circuit 150 at station M causing the operation of control device 151 therein. The operation of control device 151 will cause energizing currents to be immediately supplied to the winding of relay 152 causing immediate operation of that relay to disable the path WA at station M by opening the 65 normally closed contacts 155 in that path. Substantially T seconds later the winding of relay 153 will be energized by the currents from the output of the control device 151 which have been 70 delayed in delay circuit 154, causing the operation of that relay to open the normally closed switch contacts 156 in the input of relay 152. The relay 152, because of the hang-over in its operation, however, will not release for an additional interval of time T thereafter, at the end

of which interval it will cause the switch contacts 155 to return to their normally closed condition rendering the path WA operative thereafter for transmitting current thereover.

Another portion of the west subscriber's speech currents will be diverted into the control circuit 132 at station B causing the operation of control device 133 therein. The operation of control device 133 will immediately supply energizing currents to relay 134 causing its immediate operation to open-circuit the input of path WA at station B by opening the normally closed switch contacts 140 in that path.

The west subscriber's speech currents have now 15 obtained exclusive control of all the switching circuits in the system.

Substantially d_1 seconds after the west subscriber's speech currents have obtained exclusive control of the system, the system is biased as regards break-ins in favor of the east subscriber, 20 under control of the west subscriber's speech currents in the following manner.

Substantially d_1 seconds after relay 134 has operated in response to operation of control device 133, the energizing currents for relay 135 which have been delayed for that interval of time of delay circuit 136 are supplied to the winding of relay 135 causing its operation to close normally open switch contacts 141 in control circuit 137, 30 thereafter rendering that circuit operative to transmit energizing currents to relay 139 from the output of control device 138 when that device is operated. Relay 135 because of the hang-over in its operation will remain operated h_1 35 seconds after the west subscriber has stopped talking.

Now, let us suppose that the east subscriber associated with the circuit L_2 terminating at station B says something when he observes the west subscriber pause. The east subscriber's speech currents will be impressed by the hybrid coil H_2 on the input of the path WA and, the relay 134 having released during this pause by the west subscriber to temporarily return switch contacts 40 140 to their normally closed condition, east's speech currents will be transmitted over the path EA towards the west station A. A portion of the east speech currents will be diverted into control circuit 137 at station B causing the operation of control device 138 therein. Because of the hangover of h_1 in the operation of relay 135 the switch contacts 141 in the output of control circuit 137 are still in the closed condition so that energizing currents are supplied to the winding of relay 139 which operates to open the normally closed switch contacts 142 in the output 50 of the path EA at station B rendering that path thereafter inoperative to transmit to circuit L_2 or to the control circuit 132. Control circuit 132 55 having been thus disabled during the pause in the west subscriber's speech currents, the west subscriber will not be able to regain control of control device 133 and the east subscriber has, therefore, gained exclusive control of the switching circuits at station B.

At intermediate station M a portion of the east subscriber's speech currents are diverted into control circuit 143 causing operation of the control device 144 therein. The operation of control device 144 will cause energizing currents to be immediately supplied to the winding of relay 145 causing its operation to disable the path WA by opening switch contacts 148 therein at station M.

The energization of the winding of relay 146 in response to the operation of control device 144 will be delayed after the operation of relay 145 for an additional interval T due to the delay circuit 147 in the input of relay 146 at the end of which interval the relay 146 will operate to disable relay 145 by opening switch contacts 149.

The east subscriber's speech currents have been able to get through to the control circuit 143 at station M because the switch contacts 155 in the path WA at that station, which had been previously opened in response to the operation of control device 151 by the west subscriber's speech currents, have now returned to their normally closed condition because the input of relay 152 will have been disabled by the opening of switch contacts 156 by relay 153 in response to the operation of control device 151. The operation of relay 153 in response to operation of control device 151 has been delayed for a time interval of T after relay 152 operated due to the delay introduced by delay circuit 154. Thus, it is seen that the switch contacts 155 are returned to their normally closed condition just before the east subscriber's speech currents reach the disabling point in path WA at station M.

The main portion of the east subscriber's speech currents, the switch contacts 131 being in their normally closed condition because of the normally open switch contacts 130 in the input of relay 128, will be transmitted over the output of the path WA at station A to the hybrid coil H₁ which will impress it on the circuit L₁ over which it will be transmitted to the west subscriber.

35 A portion of the east subscriber's speech currents will be diverted from the path WA at station A into control circuit 121 causing the operation of control device 122 therein. The operation of the control device 122 will first cause the winding of relay 123 to be energized which relay will then operate to open the normally closed switch contacts 129 in the input of path EA at station A rendering that path thereafter inoperative to transmit the west subscriber's speech currents to the east subscriber or to the control circuits 126, 150 and 132. The east subscriber's speech currents have now obtained exclusive control of the switching circuits of the whole system.

40 Substantially d_1 seconds after relay 123 has operated the energizing currents from the output of control device 122 which have been delayed in delay circuit 125 will be transmitted to the winding of relay 124 causing its operation to close normally open switch contacts 130 in control circuit 126 rendering operative the input of relay 128. The system is now biased as regards break-ins in favor of the west subscriber. The west subscriber now, on perceiving a pause by the east subscriber, may break in and seize control of the system away from the east subscriber in a manner similar to that which has just been described for the converse condition.

45 From the above description, it may be noted that the mid-point echo suppressor at station M in the system of Fig. 4 functions only during operational changes, i. e., when the circuit goes from inactive into active condition, and with the circuit active, when the control of the circuit is changed from one party to another. Therefore, 50 the delay has only to be effective during this change, and may be provided for by slow-operating relays.

55 Although the invention has been described in connection with four-wire circuits employing continuous two-wire paths for transmission in

either direction between terminal stations, it is apparent that the principles of the invention apply equally well to circuits employing sections of two-wire lines for transmitting and receiving at each terminal station, respectively, and employing as an intermediate link a long two-way transmission medium, such as the air link of a two-way radio telephone circuit or the submarine cable link of a two-way submarine cable telephone circuit.

60 Although in the particular embodiments of the invention illustrated and described, mechanical relays have been shown for conditioning the transmission paths by operating movable switches to close or open-circuit the paths, the invention is not limited to circuits employing the particular conditioning means shown. For example, within the scope of the invention the transmission paths may be effectively disabled by short circuits or loss networks inserted in the paths, controlled by relays. Stationary devices having no movable elements may be employed in place of the mechanical relay shown, for example, vacuum tube relays, such as disclosed in Crisson Patent 1,647,212 issued November 1, 1926 or in the article by C. A. Beer and C. T. Evans in the Institute of P. O. Electrical Engineers (London) volume 20, pages 65 to 72, inclusive, published in 1920.

65 What is claimed is:

1. A system for transmitting signals in opposite directions between stations comprising means responsive to the signals from one station for giving exclusive directional control of the system thereto in preference to later initiated signals from the other station, and means automatically operative when said control has been obtained by said signals from one station to bias the system as regards subsequent directional control in favor of later initiated signals from said other station.

70 2. The system of claim 1 and in which said means for biasing said system is responsive directly to the signals from said one station.

75 3. A system for transmitting signals in opposite directions between stations, comprising means responsive to the initiation of signals at one of said stations for preventing transmission of signals later initiated at the other station to said one station, while allowing transmission of the signals initiated at said one station to said other station, and means also responsive to the signals initiated at said one station for altering the circuit connections at said other station to bias the system as regards subsequent directional control of transmission in favor of later initiated signals at said other station.

80 4. The system of claim 3 and in which the last-mentioned means operates to bias the system in favor of later initiated signals from said other station after directional control of the system has been obtained by the earlier initiated signals from said one station.

85 5. In a system for transmitting signals in opposite directions between stations, control circuits for determining directional control of transmission therein, means responsive to signals initiated at one station for controlling said control circuits so as to permit transmission of said signals from said one station to another station, while preventing transmission of signals later initiated at said other station to said one station, and means automatically operative after directional control of the system has been obtained for the signals initiated at said one station, to rearrange said control circuits so as to permit later initiated sig- 90 75

nals from said other station to immediately obtain directional control of the system at a slight pause in the transmission of the signals from said one station.

- 5 6. In a system for transmitting signals in opposite directions between stations, control circuits for determining directional control of transmission therein, means responsive to signals initiated at one station for controlling said control circuits so as to allow transmission of said signals from said one station to another station, while preventing transmission of signals later initiated at said other station to said one station and means for rearranging said control circuits after directional control of the system has been obtained by the signals initiated at said one station, to bias the system as regards subsequent directional control thereof in favor of signals later initiated at said other station.
- 20 7. A four-wire signaling circuit comprising normally operative, oppositely directed one-way transmission paths connecting the terminals of said circuit, an echo suppressor unit at or near each terminal comprising means connected to the incoming one-way path thereat and responsive to signals therein to disable the input of the outgoing path at said terminal, and means connected to the outgoing path and responsive to signals therein to disable the means for disabling said outgoing path, a normally disabled control circuit at each terminal which when operative is responsive to signals in the outgoing path thereat to disable the incoming path at the same terminal and means at each terminal responsive to the signals in the incoming path thereat for rendering the normally disabled control circuit at the same terminal operative a given time after the outgoing path is disabled in response to the incoming signals.
- 40 8. A four-wire signaling circuit comprising normally operative, oppositely directed one-way paths connecting the terminals of the circuit, an echo suppressor unit at or near each terminal of the four-wire circuit, each unit comprising means connected to the outgoing one-way path and responsive to outgoing signals therein to disable the output of the incoming one-way path, and means connected to the incoming path and responsive to incoming signals therein to disable the means for disabling the incoming path, a normally disabled control circuit at each terminal which when operative is responsive to signals in the outgoing path thereat to disable the incoming path at the same terminal, and means at each terminal and responsive to signals

in the incoming path thereat for rendering the normally disabled control circuit at the same terminal operative a given time after the incoming path-disabling means at said same terminal has been disabled in response to the same signals. 5

9. A two-way signaling system comprising transmitting and receiving circuits at each terminal thereof, and an echo suppressor unit at or near each terminal comprising means responsive to signals in the receiving circuit thereat to disable the transmitting circuit at the same terminal, means responsive to signals in said transmitting circuit to disable the transmitting circuit disabling means, a normally disabled control circuit which when operative is responsive to signals in said transmitting circuit to disable said receiving circuit, and means responsive to signals in said receiving circuit a definite time after they have disabled said transmitting circuit, to render said control circuit operative. 10 15 20

10. The system of claim 9 and in which said means for disabling the transmitting circuit disabling means operates in response to signals in said transmitting circuit substantially a time T 25 after the initiation of said signals therein, where T is the transmission time between the terminals of said system.

11. A two-way signaling system comprising transmitting and receiving circuits at each terminal thereof, and an echo suppressor unit at or near each terminal of said system, each unit comprising means connected to the transmitting circuit and responsive to signals therein to disable the receiving circuit at a time T after the 30 initiation of, and to maintain it disabled an additional time interval T after cessation of said signals in said transmitting circuit, where T equals the transmission time between the terminals of said system, means connected to the receiving 35 circuit and responsive to signals therein to disable the receiving circuit disabling means, a normally disabled control circuit which when operative is responsive to signals in said transmitting circuit to disable the receiving circuit and to maintain it disabled for a definite time after the controlling signals cease, means responsive to signals in the receiving circuit to render the normally disabled control circuit operative a given time after the receiving circuit disabling means is 40 45 50 disabled in response to the signals, and means to maintain said control circuit operative for a definite time after the signals in the receiving circuit cease.
